Atty

United States Patent Office.

ABRAM C. STANNARD, OF MILTON, WISCONSIN.

Letters Patent No. 89,251, dated April 20, 1869.

IMPROVED WASHING-MACHINE.

The Schedule referred to in these Letters Patent and making part of the same

To all whom it may concern:

Be it known that I, ABRAM C. STANNARD, of Milton, in the county of Rock, and in the State of Wisconsin, have invented certain new and useful Improvement in Washing-Machines; and do hereby declare that the following is a full, clear, and exact description thereof, reference being had to the accompanying drawings, and to the letters of reference marked thereon.

The nature of my invention consists in operating the beater-rock shaft by a tortuously-grooved cam-wheel, through a curved arm, furnished with a pin at its end, in combination with an oscillating spring-board pivoted at its upper edge.

In order to enable others skilled in the art to which my invention appertains, to make and use the same, I will now proceed to describe its construction and operation, referring to the annexed drawings, which form a part of this specification, and in which—

Figure 1 is a side elevation in section, and
Figure 2 is a plan view.

A represents a rectangular box, of suitable dimensions, the bottom of which forms an inclined plane, B, along the front side, as shown in fig. 1.

A suitable distance from the front side, and near the upper edge of the end-pieces of the box A, is pivoted or hinged a perforated dash-board, C, which hangs down to near the inclined plane B.

The lower edge of the perforated dash-board C rests against two spiral springs, D D, which are secured to the front side of the box A.

At the rear edges of the end-pieces of the box A are two standards, E E, between which and above the box is placed a shaft, F, which has its bearings in said standards, and is provided on its under side with two arms, G G, to the lower ends of which a perforated beater, H, is secured.

From the upper side of the shaft F a bent arm, J, projects upward, said arm being at its upper end, on

one side, provided with a pin, I, which fits into a groove on a cam-cylinder, K.

The shaft to which said cam-cylinder is secured has its bearings in suitable journal-boxes, on a cross-bar, L, connecting the upper ends of the two standards, E E, and on another standard, M, secured to the rear side of the box A.

This shaft is also provided with a balance-wheel, N, and crank O, by the means of which the machine is operated.

When the clothes to be washed are placed in the box, between the beater and the dash-board, and the crank O turned, it will be seen that the beater H carries the clothes up the inclined plane B, against the yielding dash-board C, and, as soon as the beater moves backward, the dash-board, operated upon by the springs D D, carries the clothes back again down the inclined plane.

I am aware that the several devices shown and described herein, when taken separately, are, of themselves, not new. My invention consists more particularly in the general arrangement and combination of the parts.

Having thus fully described my invention,

What I claim as new, and desire to secure by Letters Patent, is—

The arrangement, with the box A, of the perforated swinging board C, springs D, inclined board B, perforated beater H, arms G, and rock-shaft F, operated by the tortuously-grooved cylinder K and arm J, all substantially as shown and described.

In testimony that I claim the foregoing, I have hereunto set my hand, this 18th day of December, 1868.

ABRAM C. STANNARD.
